FOREIGN PATENT DOCUMENTS

GB 2439723 1/2008

* cited by examiner

Primary Examiner — Robert M. Spear*Assistant Examiner* — Ryan Harvey(74) *Attorney, Agent, or Firm* — Rankin, Hill & Clark LLP(57) **CLAIM**

The ornamental design for an exercise apparatus for punching, as shown and described.

DESCRIPTION

FIG. 1 is a right perspective view of an exercise apparatus for punching;

FIG. 2 is a left perspective view thereof;

FIG. 3 is a front perspective view thereof;

FIG. 4 is a top view thereof;

FIG. 5 is a left side view thereof, the right side view being a mirror image;

FIG. 6 is a front view thereof; and,

FIG. 7 is a bottom view thereof.

The broken lines in the drawings, which illustrate environmental structure or boundaries of the exercise apparatus for punching, do not form a part of the claimed design.
